SAMPLE BOX MAKING MACHINE

Peter Jagusch, Elmwood Park, Ill.

Application February 27, 1936, Serial No. 66,006

7 Claims. (Cl. 93—58.2)

This invention relates to sample box making machines.

It is an object of this invention to provide an improved sample box making machine which is relatively simple and inexpensive in construction and efficient in use.

Another object of the present invention is to provide a new and improved device for forming score or crease lines in fibrous material or stock such, for example, as cardboard, from which a sample box or carton may be made.

A further object of the present invention is to construct the new sample box making device in such a manner that the material or stock from which the sample box is made may be readily positioned, relative to the scoring and creasing dies, so as to form the score or crease lines at the desired and predetermined points in the material.

An additional object of the invention is to provide, in the new sample box making machine, a novel gauge for properly and accurately positioning the stock or material relative to the scoring or creasing dies so as to form sample boxes of various sizes.

Still another object of the present invention is to provide a novel box making machine which is especially adapted for use in forming sample boxes of cardboard or analogous material.

In the art of making boxes or cartons of fibrous stock, it is common for a box manufacturer to be called upon to make numerous specimens or sample boxes, and the customary practice heretofore in the art has been to form these specimen or sample boxes upon the machines which are used for making commercial boxes, thereby making it necessary to stop the operation of the machines which are used for making the commercial boxes in order to make the specimen or sample boxes, thus causing a considerable loss of time and labor in stopping and starting the machines upon which the commercial boxes are made.

Another object of the present invention therefore is to provide a sample box making machine by means of which specimen or sample boxes may be formed independently of, and without interfering with, the operation of the machines on which the commercial boxes are made.

Other objects will appear hereinafter.

The invention consists in the novel combination and arrangement of parts to be hereinafter described and claimed.

The invention will be best understood by ref-

erence to the accompanying drawings showing the preferred form of construction, and in which:

Fig. 1 is a front end elevational view of a preferred form of the new sample box making machine;

Fig. 2 is a vertical longitudinal sectional view of the same on line 2—2 in Fig. 1;

Fig. 3 is a transverse sectional view on line 3—3 in Fig. 1;

Fig. 4 is a transverse sectional view of the slide- 10
able guide and indicators, on line 4—4 in Fig. 1;

Fig. 5 is a fragmentary perspective detail view 15
of the new machine showing the creasing dies
associated with the same;

Fig. 6 is a vertical sectional view on line 6—6 in 15
Fig. 5;

Fig. 7 is a fragmentary perspective view of the 20
new machine showing the scoring dies associated
with the same;

Fig. 8 is a vertical sectional view on line 8—8 20
in Fig. 7; and

Fig. 9 is a fragmentary plan view of a piece of 25
stock used in making a sample box and is herein
used to illustrate the various steps which are
described in the annexed specification.

A preferred form of the present invention is 30
shown in the drawings, is therein generally indicated at 10, and comprises a supporting frame 11
upon which is rotatably mounted a horizontally
extending shaft 12. Carried by the shaft 12, at 35
one end thereof, is a die 13 and associated with
the die 13 is a second but smaller die 14, which
may be either in the form of a creasing die 53
or a scoring die 54. The dies 13 and 14 form a
creasing and scoring unit which is generally indicated at 15, and which will be described more
fully hereinafter.

The shaft 12 and the die 13 carried thereby are, 40
in the preferred embodiment of the invention
shown in the drawings, driven by an electric
motor 16 although they may, if desired, be op-
erated by some other suitable prime mover, or
they may be manually operated, if desired.

In the preferred form of the invention which is 45
shown in the drawings, the shaft 12 is rotated by
the motor 16, through the medium of a small
pulley or sheave 21 which is carried by the shaft
22 of the motor 16, and this pulley 21 frictionally
engages a larger and speed-reducing disc 23.
The power-transmitting device 17 also includes 50
a pulley or sheave 18 which is attached to the
shaft 12, and an endless flexible power-transmit-
ting member or belt 19 which works around the
sheave or pulley 18 and around a smaller sheave
or pulley 20, this pulley 20 being mounted on a 55

stub shaft 24 which is, in turn, mounted in the frame 11. This shaft 24 also carries the disc 23.

The die 14 is rotatably, that is, loosely mounted upon a shaft 25 (Fig. 6) and this shaft 25 is, in turn, mounted in a slide block 26 which is slidably mounted upon an upright wall 27 of the frame 11, at one end of the latter, this slide block 26 and the die 14 carried thereby being adjustable vertically relative to the wall 27 of the frame 11 by means of a set screw 28 (Fig. 6).

The creasing die 53 is normally disposed in a position as shown in Figs. 5 and 6 with the flange portion 55 thereof disposed in vertical alignment with an annular groove 47 which is formed in the peripheral surface 48 of the die 13, whereas the scoring die 54 is normally disposed in a position as shown in Figs. 7 and 8 with the knife edge 56 thereof disposed out of vertical alignment with the annular groove 47, and at one side of the latter, so as to be engageable with the peripheral surface 48 of the die 13 when the slide bar 26, shaft 25 and the cutting or scoring die 54 mounted thereon are moved toward the die 13 by means of the set screw 28. The shaft 25 has a threaded stud portion 58 which is adapted to receive a threaded sleeve 59 and the latter is held in a fixed position upon the shaft 25 by a set screw 29, the threaded portion of which fits into the tapped portion of the sleeve 59 so as to bear against the stud portion 58 of the shaft 25. The dies 53 and 54 are held in their respective positions by the sleeve 59 and the set screw 29.

Attached to the wall 27 of the frame 11 is a guard 30. Formed in the wall 27 of the frame 11 is an elongated slot or opening 32 and slidably mounted in this slot or opening 32, for movement in a direction parallel to the axis of the shaft 12 and the die 13 is a supporting block 33. Attached to this block 33 for movement therewith, is a channel shaped combination guide and supporting member 31 (Fig. 4). Carried by the supporting block 33 is a set screw or clamping member 34 by means of which the slide block 33 and the guide 31 may be clamped in a preselected position.

Mounted on the upright wall 27 of the frame 11 is a scale 35 and the slide block 33 has an upwardly extending portion 36 which includes two indicators or fingers 37 and 38, the function of which will be explained hereinafter.

Mounted in the slide block 33 is a shaft or arm 39 and rotatably mounted on this arm 39 is a bearing wheel or disc 40 which bears upon the horizontal wall or guideway 41 of the guide 31, this disc or wheel 40 being urged into bearing engagement with the wall 41 of the guide 31 by means of a spring 42 which bears upon the shaft 39 (Fig. 5).

Pivotedly mounted at one end, as at 50 upon the horizontal base 49 of the machine, is a shearing knife 51 which is provided at one end with a handle 52, and arranged upon the base 49, for use in conjunction with the knife 51, in a manner which will be described more fully hereinafter, is a scale 44 (Fig. 2).

Operation

In the use of the new machine the shaft 12 and the die 13 may be rotated through the medium of the power-transmitting device 17, or by any other suitable power-transmitting device, or manually, if desired.

It will be assumed, for example, and for the purpose of illustrating the present machine, that

it is desired to crease a piece of fibrous stock or material for making a sample box or carton which is three (3) inches over all, that is, a cube having dimensions of three (3) inches. In this event the operator of the present machine will first see that the die 53 is properly mounted upon the shaft 25 with the flange 55 thereof in vertical alignment with, and directly above, the annular groove 47 which is formed in the peripheral surface 48 of the die 13. If the stock which is to be used is not approximately of the desired dimensions the operator may first place the same upon the work table or bed plate 49 and trim the same, by means of the knife 51 to exactly the proper dimensions, using the scale 44 as a guide, whereupon he may then move the slide block 33 along the frame 11, in the guide slot 32, until the indicator finger 37 comes opposite or into registration with the numeral 3 on the scale 35 (Fig. 5), whereupon the slide block 33 and the guide 31 may be clamped in position by means of the set screw 34. The right hand marginal edge portion of the stock (as the same would appear in Fig. 5) may then be placed upon the combination guide and support 31 with the bottom of the same resting upon the bottom wall 41 of the member 31 and with the right hand edge thereof (as the same would be seen in Fig. 5) bearing against the vertical side wall 46 of the guide 31. The free (left side, Fig. 5) end of the stock 45, being supported by the operator, the rotating action of the die 13 (counterclockwise, Fig. 5) will draw it through the machine, that is, between the dies 14 and 13 whereupon the die 53, traveling in the groove 47, will form the desired crease line in the stock and this crease line will thus be formed in the stock a distance, in the present example, which is exactly three inches from the marginal edge of the stock which is disposed in engagement with the vertical wall 46 of the guide 31; it being noted that when the indicator or finger 37 is in registration with the "3" inch mark on the scale 35 the vertical side wall 46 of the guide 31 is disposed exactly three inches from the vertical center line of the annular groove 47 which is formed in the die 13 and, likewise, exactly three inches from the vertical center of the flange 55 of the die 53 when the latter is in vertical alignment or registration with the annular groove 47 in the die 13. It will be seen, therefore, that the indicator or finger 37 indicates, on the scale 35, the distance which the vertical wall 46 of the guide 31 is disposed from the annular creasing groove 47 in the die 13, whereas, as will be explained more fully hereinafter, the indicator or finger 38 indicates the distance which the vertical side wall 46 of the guide 31 is disposed from the vertical center line of the knife edge 56 on the scoring die 54 when the latter is disposed in cutting or scoring position, as in Fig. 8.

In the foregoing manner a crease line 57 is formed in the stock 45 (Fig. 5) and the foregoing operation may be repeated to form the necessary four crease lines in the stock (Fig. 9) by turning the stock around and successively engaging the marginal edges thereof with the vertical wall 46 of the guide 31, the free end of the stock 45 being supported at each operation, so as to draw the latter through the machine, that is, between the dies 14 and 13. During this operation, as well as during the cutting or scoring operation presently to be described, the member 30 acts as a guard to prevent the op-

erator from getting his fingers between the dies 14 and 13.

It will be seen from the foregoing description that by adjusting the guide 31 and the slide 5 block 33 carried thereby, relative to the scale 35, and then performing the foregoing creasing operation, crease lines may be formed in the stock at various predetermined distances from the marginal edges of the stock, that is, the stock 10 may be creased for forming sample boxes of various sizes or dimensions, with relatively little or no difficulty.

In the present example, and having reference to Fig. 9, the four crease lines 57 formed in the 15 stock 45 divide the latter into nine (9) sections of which one section identified as "b" forms the bottom of a sample box or carton, and the four identified by the letter "s" form the side walls of the said sample container. The four 20 other and remaining sections of the piece of stock shown in Fig. 9, and each of which is identified by a letter "x", are removed from the stock by a cutting operation which is as follows:

The creasing die 53 which is used in the creasing operation is removed from the shaft 25, by first removing the set screw 29 and the sleeve 59, and this creasing die 53 is replaced by the cutting die 54 which is fixed into its relative position upon the shaft 25, with respect to the 25 die 13, by the sleeve and set screw 59 and 29 respectively (Figs. 7 and 8). In this position the cutting edge of the die 54 will be disposed in bearing engagement or contact with the peripheral surface 48 of the die 13, whereupon the 30 slide block 33 and the guide 31 may be adjusted (left to right, Fig. 5) until the indicator finger 38 comes into registration or alignment with the numeral "3" on the scale 35, and at 35 this time the side wall 46 of the guide 31 will be disposed exactly three inches from the center line of the cutting edge 56 of the die 54 (when the latter is disposed in cutting position, as in Fig. 8). The guide 31 and slide block 33 may 40 then be clamped in position, by means of the set screw 34, whereupon the stock may be run through the machine, that is, between the dies 13 and 14 (the die 14 being at this time the cutting die 54 which is positioned as in Fig. 8). During this operation, the die 14, being disposed 45 in bearing engagement with the peripheral surface 48 of the die 13, at one side of the groove 47, will cut the stock 45 along the line 60 (Fig. 9) and by turning the stock around and repeating the foregoing operation the necessary number 50 of lines 60' may be cut in the stock 45.

It will be noted that by adjusting the slide 55 block 26 and the die 14 vertically, relative to the die 13 and the annular creasing groove 47 therein, by means of the set screw 28, the die 14 may be adjusted or spaced vertically, relative 60 to the die 13, to accommodate the same to the thickness of the stock.

In the use of the present machine the small 65 wheel or disc 40 bears under the action of the spring 42, against the horizontal wall 41 of the guide 31, and being disposed at an angle, relative to the stock and the guide 31, the disc 40 urges the right hand marginal edge of the stock against the vertical wall 46 of the guide 31, as 70 the stock is drawn between the dies 14—13, so as to assure that the crease line formed in the stock or the line cut therein, will be disposed at the desired and intended distance from the vertical wall 46 of the guide 31.

75 While I have illustrated and described the

preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters 10 Patent is:

1. A sample box making machine comprising a supporting frame, a shaft rotatably mounted upon said supporting frame, means for operating said shaft, a circular die carried by said shaft at one axial end of the latter, and having an annular groove formed in its peripheral surface, a circular creasing die rotatably mounted upon said frame above the said first-named die, means for adjusting the said second-named die vertically relative 15 to the said first-named die as to move the same into and out of the said annular groove formed in the said first-named die whereby the said dies may coact to form, at different times, crease lines 20 in pieces of stock of various thicknesses inserted therebetween, a guide slidably mounted upon said supporting frame for horizontal movement and axially relative to the said dies and shaft, said guide including a horizontal guideway extending 25 transversely of the said supporting frame and shaft and said guideway including a vertically extending side wall, a horizontally extending scale mounted upon said supporting frame and extending axially of said shaft and having indicia 30 thereon representing the distance between the vertical center of the said annular groove in the said first-named die and the said vertically extending wall of said guideway, a slide block carried by said guide and including an indicator 35 portion or finger movable along and relative to said scale, and means for releasably clamping said guide and indicator in a fixed position relative to said supporting frame and said scale whereby when the said second-named die is adjusted so 40 that the vertical center line of the same and the vertical center line of the said groove are coincident a piece of stock moved through the machine between the said dies and having one marginal edge thereof bearing against the said side 45 wall of said guide will have a crease line formed 50 therein a distance from the said marginal edge of said stock corresponding to the distance indicated by the said finger upon said scale.

2. A sample box making machine comprising a supporting frame, a shaft rotatably mounted 55 upon said supporting frame, means for operating said shaft, a circular die carried by said shaft at one axial end of the latter, a circular scoring die rotatably mounted upon said frame above the said first-named die, means for adjusting the said second-named die vertically relative to the said first-named die as to move the same into and out of 60 engagement with the peripheral surface of the said first-named die whereby the said dies may coact to form, at different times, score lines in 65 pieces of stock of various thicknesses inserted therebetween, a guide slidably mounted upon said supporting frame for horizontal movement axially relative to said dies and shaft, said guide including a horizontal guideway extending transversely 70 of the said supporting frame and shaft and said guideway including a vertically extending side wall, a horizontally extending scale mounted upon said supporting frame and extending axially of said shaft and having indicia thereon repre- 75

senting the distance between the vertical center of the said second-named die and the said vertically extending wall of said guideway, a slide block carried by said guide and including an indicator portion or finger movable along and relative to said scale, means for releasably clamping said guide and indicator in a fixed position relative to said supporting frame and said scale, and means carried by said slide block for urging a marginal edge portion of a piece of stock disposed upon said guideway against the said vertical wall of the same whereby when the said second-named die is adjusted so that the vertical center line of the same is a predetermined distance from the said vertically extending wall of said guideway, and a piece of stock is inserted into the machine between the dies, and with one marginal edge thereof bearing against the said wall of said guideway, the said stock will have a score line formed therein a distance from the said marginal edge of said stock corresponding to the distance indicated by the said finger on said scale.

3. A box making machine comprising a supporting frame, a circular die rotatably mounted upon said supporting frame and having an annular groove formed in its peripheral surface, a creasing die including a substantially cylindrical member having an annular flange formed thereon, and means carried by the said supporting frame above the said first-named die for rotatably mounting the said creasing die so that the said flange thereon is disposed in vertical alignment with the said annular groove formed in said first-named die, said means including a device for optionally and rotatably mounting a scoring die thereon, in place of said creasing die, and in a position wherein the vertical line of the said scoring die is out of vertical alignment with the said annular groove, said device comprising a shaft adapted to support both of said dies, at different times, said shaft having an axially inner end portion rotatably mounted in said supporting frame and having a threaded axially outer end portion, a sleeve having a threaded opening formed therein for the reception of the said outer end portion of said shaft, a set screw having an axially inner end portion threaded into the said opening in said sleeve and adapted to bear at its axially inner end against the axially outer end portion of said shaft so as to hold the said dies, at different times, in their proper and preselected positions relative to the said first-named die.

4. A box making machine comprising a supporting frame, a circular die rotatably mounted upon said supporting frame and having an annular groove formed in its peripheral surface, a creasing die including a substantially cylindrical member having an annular flange formed thereon, means carried by the said supporting frame above the said first-named die for rotatably mounting the said creasing die so that the said flange thereon is disposed in vertical alignment with the said annular groove formed in said first-named die, said means including a device for optionally and rotatably mounting a scoring die thereon, in place of the said creasing die, and in a position wherein the vertical line of the said scoring die is out of vertical alignment with the said annular groove, and means for adjustably mounting the said first-named means upon said supporting frame so that the said scoring or creasing die mounted thereon may be adjusted relative to the said first-named die so as to accommodate the said dies to pieces of stock of various thicknesses inserted therebetween, said

device comprising a shaft adapted to support both of said dies, at different times, said shaft having an axially inner end portion rotatably mounted in said supporting frame and having a threaded axially outer end portion, a sleeve having a threaded opening formed therein for the reception of the said outer end portion of said shaft, a set screw having an axially inner end portion threaded into the said opening in said sleeve and adapted to bear at its axially inner end against the axially outer end of said shaft so as to hold the said dies, at different times, in their proper and preselected positions relative to the said first-named die. 5

5. A box making machine comprising a supporting frame, a circular die rotatably mounted upon said supporting frame and having an annular groove formed in its peripheral surface, a creasing die including a substantially cylindrical member having an annular flange formed thereon, means carried by the said supporting frame above the said first-named die for rotatably mounting the said creasing die so that the said flange thereon is disposed in vertical alignment with the said annular groove formed in said first-named die, said means including a device for optionally and rotatably mounting a scoring die thereon, in place of said creasing die, and in a position wherein the vertical line of the said scoring die is out of vertical alignment with the said annular groove, said supporting frame having a horizontally extending scale thereon, a combination guide and supporting member slidably mounted on said supporting frame for supporting a marginal edge portion of a piece of stock inserted between said dies, and an indicator carried by said guide member for movement therewith along said scale and indicating on the latter the distance from the marginal edge of said marginal edge portion to the vertical center line of said annular groove, said device comprising a shaft adapted to support both of said dies, at different times, said shaft having an axially inner end portion rotatably mounted in said supporting frame and having a threaded axially outer end portion, a sleeve having a threaded opening formed therein for the reception of the said outer end portion of said shaft, a set screw having an axially inner end portion threaded into the said opening in said sleeve and adapted to bear at its axially inner end against the axially outer end of said shaft so as to hold the said dies, at different times, in their proper and preselected positions relative to the said first-named die. 10

6. A box making machine comprising a supporting frame, a circular die rotatably mounted upon said supporting frame and having an annular groove formed in its peripheral surface, a creasing die including a substantially cylindrical member having an annular flange formed thereon, means carried by the said supporting frame above the said first-named die for rotatably mounting the said creasing die so that the said flange thereon is disposed in vertical alignment with the said annular groove formed in said first-named die, said means including a device for optionally and rotatably mounting a scoring die thereon, in place of the said creasing die, and in a position wherein the vertical line of the said scoring die is out of vertical alignment with the said annular groove, said supporting frame having a horizontally extending scale thereon, a combination guide and supporting member slidably mounted on said supporting frame for supporting a marginal edge portion of a piece of stock inserted between said dies, and an indicator carried by said guide member for movement therewith along said scale and indicating on the latter the distance from the 15

marginal edge of said marginal edge portion to the vertical center line of said scoring die, said device comprising a shaft adapted to support both of said dies, at different times, said shaft having 5 an axially inner end portion rotatably mounted in said supporting frame and having a threaded axially outer end portion, a sleeve having a threaded opening formed therein for the reception of the said outer end portion of said shaft, a set 10 screw having an axially inner end portion threaded into the said opening in said sleeve and adapted to bear at its axially inner end against the axially outer end of said shaft so as to hold the said dies, at different times, in their proper and 15 preselected positions relative to the said first-named die.

7. A box making machine comprising a supporting frame, a circular die rotatably mounted upon said supporting frame and having an annular groove formed in its peripheral surface, a creasing die including a substantially cylindrical member having an annular flange formed thereon, means carried by the said supporting frame above the said first-named die for rotatably 20 mounting the said creasing die so that the said flange thereon is disposed in vertical alignment with the said annular groove formed in said first-named die, said means including a device for optionally and rotatably mounting a scoring die 25 thereon, in place of the said creasing die, and in a position wherein the vertical line of the said scor- 30

ing die is out of vertical alignment with the said annular groove, said supporting frame having a horizontally extending scale thereon, a combination guide and supporting member slidably mounted on said supporting frame for supporting a marginal edge portion of a piece of stock inserted between said dies, and an indicator carried by said guide member for movement therewith along the said scale, said indicator having two spaced fingers, one of said fingers indicating on said scale, 10 the distance between the marginal edge of the said marginal edge portion and the vertical center line of said annular groove, and the other of said fingers indicating on said scale the distance between the marginal edge of the said marginal edge portion and the vertical center line of the said scoring die, said device comprising a shaft adapted to support both of said dies, at different times, said shaft having an axially inner end portion rotatably mounted in said supporting 15 frame and having a threaded axially outer end portion, a sleeve having a threaded opening formed therein for the reception of the said outer end portion of said shaft, a set screw having an axially inner end portion threaded into the said opening in said sleeve and adapted to bear at its axially inner end against the axially outer end of said shaft so as to hold the said dies, at different times, in their proper and preselected positions relative to the said first-named die. 20

PETER JAGUSCH. 25
